UNITED STATES PATENT OFFICE.

LEONIDAS S. HUDSON, OF NEWARK, NEW JERSEY.

OVERHEAD CARRIER.

1,415,448.

Specification of Letters Patent. Patented May 9, 1922.

Application filed December 20, 1920. Serial No. 432,050.

To all whom it may concern:

Be it known that I, LEONIDAS S. HUDSON, a citizen of the United States, residing at Newark, in the county of Essex and State of New Jersey, have invented a new and useful Overhead Carrier, of which the following is a specification.

This invention relates to a knockdown structure for use as a track for a traveling conveyor, one of its objects being to provide a track of novel construction, made up of units which can be adjusted angularly relative to each other, thereby to guide a conveyor to any desired point or points.

15 A further object is to provide a structure of this character which is strong and durable and can be set up and taken down easily.

Another object is to provide a structure especially suited for use in concrete construction work, it being possible to employ it in the operation of an overhead conveyor provided for carrying the materials to a mixer, and also to use it for conveying the mixture from the mixer or from a hoist, to 25 the points of use.

With the foregoing and other objects in view which will appear as the description proceeds, the invention consists of certain novel details of construction and combinations of parts which will be hereinafter more fully described and pointed out in the claims it being understood that various changes may be made in the construction and arrangement of the parts without departing from the 35 spirit or sacrificing any of the advantages of the invention as set forth in the accompanying claims.

In the drawings the preferred form of the invention has been shown.

40 In said drawings—

Figure 1 is a side elevation of the structure, parts being broken away.

Figure 2 is an enlarged transverse section therethrough.

45 Figure 3 is a plan view of a portion of the track and its supports.

Figure 4 is a longitudinal section through a portion of the track.

50 Figure 5 is a plan view of one of the track joints.

Figure 6 is a detail view partly in section of portions of one of the supports and one of the braces.

Referring to the figures by characters of 55 reference, 1 designates supporting legs or standards arranged in pairs and provided at

their upper ends with extensions 2 at the bases of which are provided inwardly extending shoulders 3. These standards are oppositely disposed, the standards of each pair converging upwardly and being connected at their upper ends by cross braces 4 in the form of strips having openings 5 into which the extensions 2 project. Pivottally connected to the lower portion of one standard of each pair is a lower brace 6 the free end portion of which has a slot 7 extending thereinto from its lower edge adapted to receive a stud or projection 8 extending from the other standard of said pair.

Two pairs of standards are provided for each unit of the structure and resting on the shoulders 3 of the standards are angle rails 9 the upstanding outer side flanges of which are detachably secured to the extensions 2 by bolts 10, as shown. The standards are connected to the rails near the ends of the rails and the parts are preferably reinforced by braces 11 diagonally arranged between the standards and the rails as shown. Each 80 brace is detachably connected at one end, as by a hook 12 and eye or loop 13 so that when the structure is knocked down the parts can be folded readily.

One end of each rail 9 has an ear 14 extending therefrom flush with the top surface of the rail base while a recess 15 is formed under the ear. The other end of each rail has an ear 16 extending from the bottom surface of the rail and provided with a recess 17 thereabove. The ears are provided with openings 18 so that when the units of the structure are assembled the ears 14 of one unit will lap the ears 16 of the next unit and coupling bolts or pins 19 can be inserted into the registering openings 18 and held by cotter pins or the like. With the units thus assembled they can be adjusted angularly to extend the track in any desired direction.

Obviously any desired number of units can be assembled. The end units of the structure will be provided at their free ends with cross strips 20 and 21 respectively. The strip 21 is provided at the center with a sheave 22 while the strip 20 is provided at 105 the center with sheaves 23 and 24.

A carriage 25 of any desired construction is mounted to travel on the rails and is held against lateral displacement by the upstanding flanges of the rails and between which the wheels of the carriage travel. See figure 2. This carriage has a conveyor bucket 26

suspended therefrom and the bucket can be of any construction desired. A cable 27 is connected to one end of the carriage and extends over the sheave 22 and thence back the 5 full length of the structure to the sheave 23 and to a drum 28 driven by an engine, not shown. Another cable 29 is wound on the drum 28 in the opposite direction and extends over the pulley 24 to the other end of 10 the carriage. Thus the carriage 25 can be operated toward or from a chute 30 used for directing materials into the bucket 26.

It is to be understood that the structure can be carried from place to place in a 15 knocked down condition and the parts can be set up readily either on the ground for the purpose of conveying materials to a concrete mixer or on a floor of a building under construction where it can be used for 20 conveying the mixture from a hoist to different places where the mixture is to be spread or deposited. With this arrangement it becomes unnecessary to use a number of wheel barrows as heretofore and, consequently, the 25 runways that have been necessary, the large number of employees, etc., can be dispensed with. As a result the cost of the construction work can be greatly reduced and the work can be materially expedited. The 30 structure can also be used to advantage in road building, as will be apparent.

What is claimed is:—

1. A structure of the class described including a series of units each including supports arranged in pairs, upwardly projecting extensions upon the supports, opposed rails bearing on the supports and secured to the extensions, said rails having upwardly extending guide flanges, cross braces detach-

40 ably engaging the extensions, braces detachably connecting the lower portions of the supports, and means for detachably and pivotally connecting the ends of the rails of abutting units.

2. A structure of the class described including a plurality of units each including angle rails, a pair of supports detachably connected to the rails at each end, extensions upon the upper ends of the supports, cross braces engaging and removable from the extensions, cross braces connecting the lower portions of the supports, ears projecting from the ends of the rails, the ears on the rails of each unit lapping the ears on the rails of the next adjoining units, means for 50 detachably and pivotally connecting thelapping ears, a carriage movable along the rails, and cables extending longitudinally of the rails for shifting the carriage longitudinally of the rails in either direction. 55

3. A structure of the class described including a series of units each comprising pairs of supports, parallel rails mounted on the supports, extensions upon the supports and above the rails, braces above the rails 65 and connecting the extensions, braces below the rails and connecting the supports, said braces, supports and rails being detachably connected, and detachable pivotal connections between the rails of adjoining sections. 70

In testimony that I claim the foregoing as my own, I have hereto affixed my signature in the presence of two witnesses.

LEONIDAS S. HUDSON.

Witnesses:

IVE E. SIMPSON,
AGNES ROCKELLI.
